Primary Examiner — Holly E Thurman

(57) **CLAIM**

The ornamental design for a camera stabilizer, as shown and described.

DESCRIPTION

1. Camera stabilizer
- 1.1: Perspective
- 1.2: Front
- 1.3: Rear
- 1.4: Right
- 1.5: Left
- 1.6: Bottom
- 1.7: Top

1 Claim, 7 Drawing Sheets(56)
